Filed Apr. 7, 1965, Ser. No. 446,202
7 Claims. (Cl. 170—151)

The present application is a continuation-in-part of our copending application, Serial No. 239,866, filed November 14, 1962 and entitled Cycloidal Ship Propeller.

This invention relates to cycloidal propellers, particularly for ships, said propellers having a blade wheel body which is adapted for being rotatably supported and which blade wheel body carries a plurality of blades extending substantially parallel to the axis of rotation of the body and pivotally mounted on the body. These blades are uniformly circumferentially distributed on the body along a blade circle which is co-axial with the axis of rotation of the body.

With propellers of the cycloidal type, the blades are tilted about a central axis thereof conforming to the axis of rotatable support of the blades to change the angle of attack of the blades, thereby to obtain propulsion in a direction at right angles to the axis of rotation of the blade wheel body. The individual blades of the propeller are connected through a blade actuating linkage system, a so-called kinematic, which includes a central control disc common to all of the blades and which is operable from outside the blade body for adjusting the linkage.

The linkage system includes at least one lever fixed to the respective blade, which may be termed a blade lever, and also includes a connecting rod linked to the blade lever and, furthermore, includes a crank lever pivotally connected in the region of the junction of the arms thereof to the blade wheel body with one end of one arm of the crank lever being connected to the connecting rod while the end of the other arm of the lever is connected to the control disc.

With many ships employing cycloidal propellers, two propellers are required to obtain the propulsive effort desired and, when the ship is on a straight course, it is desirable to compensate for the respective torques of the two propellers by causing them to rotate in respectively opposite directions.

With known cycloidal propeller blade actuating linkage systems as set forth, for example, in United States Patent No. 2,978,036, the drawback is encountered that, with propellers rotating in respectively opposite directions, the blade wheel body and the blade actuating linkage system has to be designed differently for propellers rotating in clockwise direction than for propellers rotating in counter-clockwise direction. This in turn means that for producing clockwise rotating propellers, machine shop drawings, models, devices and similar manufacturing aids have to be produced other than what is necessary for counter-clockwise rotating propellers so that the cost for the manufacture and the stockkeeping of the propellers is considerably increased.

It is, therefore, an object of the present invention to provide a cycloidal ship propeller, which will overcome the above mentioned drawbacks.

It is another object of this invention to provide a cycloidal ship propeller and in particular the blade actuating linkage system in such a way that the same type of blade wheel body may be employed for propellers rotating in clockwise direction and for propellers rotating in counter-clockwise direction.

These and other objects and advantages of the invention will appear more clearly from the following specifi-

cation in connection with the accompanying drawings, in which:

FIGURES 1, 2 and 3 diagrammatically illustrate three embodiments of a cycloidal ship propeller with a blade actuating linkage system according to the present invention; and

FIGURE 4 is a view showing the propeller of FIGURE 1 with the control disc shifted off center.

General arrangement.—In order to overcome the drawbacks outlined above with heretofore known linkage systems for cycloidal ship propellers, according to the present invention, the axis of the pivot by means of which the two-arm lever of the blade actuating linkage system is linked to the blade wheel body is arranged in a radial plane defined by the axis of rotation of the blade wheel body and the pivot axis of the respective blade actuated by said blade actuating linkage system.

A blade actuating linkage system designed in this way makes it possible to produce one and the same type blade wheel body for propellers rotating in clockwise direction as well as for propellers rotating in counter-clockwise direction. Thus, instead of providing two blade wheel bodies as was heretofore necessary, when employing a blade wheel linkage system according to the invention, only one type of blade wheel body is necessary so that the costs for keeping stock and replacement parts will be greatly reduced and the replacement of the parts will be greatly simplified.

Structural arrangement.—Referring now to the drawings in detail, it should be noted that, in FIGURES 1, 2 or 3, the blades are illustrated in their middle position, i.e., in a position in which the blade is tangential to the circle on which the pivot axis of said blade is located.

As will be seen from the figures in the drawings in which the same elements have been designated with the same reference numerals, the blade wheel body 1 of the cycloidal propeller, which blade wheel body is rotatably journaled in the ship body, there is provided a control disc 3 common to all of the blades 2 and operable from the outside of the blade wheel body. In addition thereto, within said rotatable blade wheel body 1 there is provided a number of blade actuating linkage systems corresponding to the number of the blades with which the blade wheel body is equipped. For purposes of clarity, however, each of the various FIGURES 1 to 3 illustrates one blade wheel actuating linkage system only.

According to the present invention, the blade actuating linkage system as shown in FIGURE 1 is so designed that the lever arms of the two-arm lever linked by a flat link to the blade wheel body confine on the side of the link pivot an angle of 170°. According to a further development of the invention, as shown in FIGURE 2, the ratio of the length of the lever arm connected to the control disc to the length of the lever arm connected to the connecting rod is about 1.2:1. Also with a blade actuating linkage system with a two-arm lever confining an angle of 180° therebetween, as shown in FIGURE 3, the same ratio of the lever arms of the two-arm lever is advantageous.

Referring more specifically to FIGURES 1, 2 and 3, it will be noted that the two-arm lever 7a is pivotally connected to the blade wheel body 1 by means of a flat link 7b. Furthermore, the double lever 7a connected through link 7b with pivot 6 is so designed that its lever arms which are of equal length confine with each other an angle of 170°. In the embodiment of FIGURE 1, the pivot 4 connecting the two-arm lever 7a to the control disc 3 is spaced from the center 11 of the disc 3. In the embodiment shown in FIGURE 2, the ratio of the lever arm length of lever arm b of the two-arm lever 7a to the length of the lever arm a connected to connecting rod 5

is about 1.2:1, and the lever arms of the two-arm lever confine with each other an angle of 170°. Also in this case the pivot 4" connecting the two-arm lever to the control disc 3 is spaced from the center of the disc.

According to the embodiment of FIGURE 3, the lever arm ratio also is approximately 1.2:1 and the angle confined by said lever arms *a* and *b* is 180°. In this embodiment, the pivot 4" in contrast to FIGURES 1 and 2 connecting the lever arm *b* to the control disc 3 is located in the center point of the control disc 3.

By appropriately selecting the angles and/or the lever arms lengths of the two-arm lever it becomes possible to adjust the blade pitch to more favorable values than was possible with heretofore known designs of blade actuating linkage systems, so that, with the present invention, better degrees of efficiency of the propeller can be obtained than were heretofore possible. Furthermore, by an appropriate design of the blade actuating linkage system according to the present invention, there will be obtained the advantage that with the control center in a position out of its central position the torques acting on the control disc and varying several times from positive to negative peaks during a rotation of the propeller will have approximately the same magnitude. Consequently, the peaks of the reciprocating forces in the individual joints of the kinematics will be reduced while simultaneously a more favorable lubrication will be obtained than was heretofore obtainable.

In FIGURE 4 a cycloidal propeller according to FIGURE 1 is shown with the control disc 3 shifted off center so that the position of the four propeller blades A, B, C and D in the four quadrants will be seen.

The center point 11 of the control disc 3 is displaced on the transverse diameter 10 from the center point of the blade wheel body 1 by a distance *e* towards the left. This displacement corresponds to a direction of attack of the force of the water on the propeller and thereby a direction of advancement of the propeller and of the ship in upward direction (with regard to the drawing), as shown in FIGURE 4 by arrow *p*. In both positions A, C of the propeller blade 2 in which the pivot axis 12 of the blade coincides with the point of intersection of the transverse diameter 10 with the blade wheel orbit 9, the blade is tangential to the blade wheel orbit as was the case before. In the two other positions, B, D which correspond to an advancing movement of the blade on the blade wheel orbit by 90° or 270° respectively with respect to the blade position A the blades are tilted out of the tangential position, in such a way that the head of the blade at the top of the view is tilted outwardly, and at the bottom of the view the head of the blade is tilted toward the inside. That blade which is designated A is after a rotation of the wheel body in the direction of the arrow *q* of 90° in the position of the blade B, after a further rotation of 90° (180° counting from the starting position) it has reached the position of the blade C, namely, again a tangential position, and finally, after a further rotation of 90° (270° from the starting position) it has reached the position of the blade D.

The problem of designing a blade wheel body and blade actuating linkage system for cycloidal propellers which can be employed for both clockwise rotating propellers and counter-clockwise propellers is by no means as simple as by merely pivoting the linkage to the blade wheel body on a line passing through the center of rotation of the blade wheel body and the pivot axis of the respective blade. Many attempts have been made to find such a linkage but heretofore such linkage systems have been defective in providing that the propeller will operate efficiently and substantially free of cavitation.

Freedom of the propeller from cavitation is extremely important, inasmuch as the reliability and safety of the propeller depends largely upon this feature. The propeller at the same time must have a high degree of efficiency throughout the useful range of pitch thereof.

The structure disclosed in the present invention solves this problem satisfactorily for the first time and provides a suitable propeller construction which provides for efficient cavitation-free operation of propeller while one and the same blade wheel body can be employed for both clockwise rotating and counter-clockwise rotating propellers. The blades can, of course, be reversed on the propeller body when the direction of rotation of the propeller body is reversed and by forming the linkage connecting the control plate with the blade levers of flat members, such as from stamped sheet metal parts or flat cast, or forged members, the linkage members themselves can also be employed for propellers of both senses of rotation. It will be evident that the provision of suitable blade actuating linkage system and a suitable blade wheel body in accordance with the principles of the present invention greatly reduces the cost of manufacture of the propellers and reduces the inventory of parts and the like.

It is, of course, to be understood that the present invention is, by no means, limited to the particular constructions shown in the drawings but also comprises any modifications within the scope of the appended claims.

What is claimed is:

1. A cycloidal ship propeller comprising: a blade wheel body rotatable on a central axis, a plurality of blades arranged along a circle concentric with said blade wheel central axis and in substantially uniformly spaced relationship to each other, pivot means pivotally supporting said blades on said blade wheel body and each pivot means defining a pivot axis for its respective blade, said pivot axes being substantially parallel to each other and to said central axis, each of said blades being capable of an oscillating movement about its pivot axis and about a middle position of the blade in which the respective blade is tangential to the circle along which the pivot axes of said blades are arranged, adjustable control means common to all of said blades and movable selectively from a central position coaxial with said central axis of said blade wheel body into any one of a plurality of positions eccentric with regard to said central axis of said blade wheel body and vice versa to govern the oscillating movement of said blades, a plurality of blade actuating linkage systems respectively operatively connecting said adjustable control means with said blade pivot means so that each of said blades will be operable in response to a rotation of said wheel body and while said adjustable control means occupies any of its possible positions to carry out an oscillating movement having the predetermined magnitude of the blade angles which correspond to the respective circular positions of the pivot axes of the blades during their circular movement with said blade wheel body, each of said blade actuating linkage systems comprising at least one lever operatively connected to the respective blade pivot means and also comprising a connecting rod linked to said lever, each of said blade actuating linkage systems furthermore comprising a two arm lever having one of its arms connected to said connecting rod and having its other arm pivotally connected at the center of said adjustable control means, a link pivotally connecting the two-arm lever in the region of the junction of the two arms thereof to a point on the blade wheel body, the two arms of said two-arm lever forming with each other an angle of approximately 170°, said point on the blade wheel body being located in a radial plane passing through the axis of rotation of said blade wheel body and through the axis of the pivotal connection of the respective blade with said blade wheel body and also being located between said axes, the arrangement being such that for each blade and the blade adjusting linkage system pertaining thereto, in the central position of said control means, with regard to the direction of rotation of said wheel body, said lever and said rod pertaining to said blade actuating linkage system, are located behind said radial plane, said angle being located on the same side of said two-arm lever as said link.

2. A cycloidal ship propeller comprising: a blade wheel body rotatable on a central axis, a plurality of blades arranged along a circle concentric with said blade wheel central axis and in substantially uniformly spaced relationship to each other, pivot means pivotally supporting said blades on said blade wheel body and each pivot means defining a pivot axis for its respective blade, said pivot axes being substantially parallel to each other and to said central axis, each of said blades being capable of an oscillating movement about its pivot axis and about a middle position of the blade in which the respective blade is tangential to the circle along which the pivot axes of said blades are arranged, adjustable control means common to all of said blades and movable selectively from a central position coaxial with said central axis of said blade wheel body into any one of a plurality of positions eccentric with regard to said central axis of said blade wheel body and vice versa to govern the oscillating movement of said blades, a plurality of blade actuating linkage systems respectively operatively connecting said adjustable control means with said blade pivot means so that each of said blades will be operable in response to a rotation of said wheel body and while said adjustable control means occupies any of its possible positions to carry out an oscillating movement having the predetermined magnitude of the blade angles which correspond to the respective circular positions of the pivot axes of the blades during their circular movement with said blade wheel body, each of said blade actuating linkage systems comprising at least one lever operatively connected to the respective blade pivot means and also comprising a connecting rod linked to said lever, each of said blade actuating linkage systems furthermore comprising a two-arm lever having one of its arms connected to said connecting rod and having its other arm pivotally connected at the center of said adjustable control means, the ratio of the length of that arm of said two-arm lever which is connected to said adjustable control means to the length of the other arm of said two-arm lever being about 1.2:1, a link pivotally connecting the two-arm lever in the region of the junction of the two arms thereof to a point on the blade wheel body, said point on the blade wheel body being located in a radial plane passing through the axis of rotation of said blade wheel body and through the axis of the pivotal connection of the respective blade with said blade wheel body and also being located between said axes, the arrangement being such that for each blade and the blade adjusting linkage system pertaining thereto, in the central position of said control means, with regard to the direction of rotation of said wheel body, said lever and said rod and also said two-arm lever and said link all pertaining to said blade actuating linkage system, are located behind said radial plane.

3. A cycloidal ship propeller comprising: a blade wheel body, a plurality of blades pivotally supported by said blade wheel body and having their pivot axes arranged along a circle in substantially uniformly spaced relationship to each other, said pivot axes being substantially parallel to each other, each of said blades being capable of an oscillating movement about its pivot, adjustable control means common to all of said blades and movable selectively from a central position coaxial with said blade wheel body into any one of a plurality of positions eccentric with regard to said blade wheel body and vice versa to govern the oscillating movement of said blades, each of said blades comprising a pivot and being oscillatable about a middle position thereof in which the respective blade is tangential to the circle along which the pivot axes of said blade are arranged, a plurality of blade actuating linkage systems respectively operatively connecting said adjustable control means with said blades, each of said blade actuating linkage systems comprising at least one lever operatively connected to the respective blade pivot and also comprising a connecting rod linked to said lever, each of said blade actuating linkage sys-

tems furthermore comprising a two-arm lever pivotally connected to said blade wheel body and having one of its arms connected to said connecting rod and having its other arm pivotally connected at the center of said adjustable control means, the arrangement being such that for each blade and the linkage system pertaining thereto the axis of the pivotal connection of the two-arm lever of the respective linkage system with said blade wheel body is located in the radial plane which passes through the axis of rotation of said blade wheel body and through the axis of the pivotal connection of the respective blade with said blade wheel body.

4. A cycloidal ship propeller according to claim 3 in which, with respect to the direction of rotation of said wheel body, each said blade actuating linkage system is located behind said radial plane pertaining thereto.

5. A cycloidal ship propeller comprising: a blade wheel body, a plurality of blades pivotally supported by said blade wheel body and having their pivot axes arranged along a circle in substantially uniformly spaced relationship to each other, said pivot axes being substantially parallel to each other, each of said blades being capable of an oscillating movement about its pivot, adjustable control means common to all of said blades and movable selectively from a central position co-axial with said blade wheel body into any one of a plurality of positions eccentric with regard to said blade wheel body and vice versa, each of said blades comprising a pivot, a plurality of blade actuating linkage systems respectively operatively connecting said adjustable control means with said blades, each of said blades actuating linkage systems comprising at least one lever operatively connected to the respective blade pivot and also comprising a connecting rod linked to said lever, each of said blades actuating linkage systems furthermore comprising a two-arm lever having one of its arms connected to said connecting rod and having its other arm pivotally connected at the center of said adjustable control means, link means linked on one hand to said two-arm lever between the end portions thereof and being on the other hand pivotally connected to said blade wheel body, the arrangement being such that for each blade and the linkage system pertaining thereto the axis of the pivotal connection of said link means with said blade wheel body is located in a radial plane passing through the axis of rotation of said blade wheel body and through the axis of the pivotal connection of the respective blade with said blade wheel body, the ratio of the length of that arm of said two-arm lever which is pivotally connected to said adjustable control means to the length of that arm of said two-arm lever which is connected to said connecting rod being within the range of from 1.2 to 1.

6. A cycloidal ship propeller according to claim 5, in which each of said blades oscillates about a middle position in which the blade is tangential to the circle along which the pivot axes of said blades are arranged, and in which the two arms of said two-arm lever confine with each other an angle of about 170 degrees.

7. A cycloidal ship propeller comprising: a blade wheel body rotatable on a central axis, a plurality of blades pivotally supported by said blade wheel body and having their pivot axes arranged along a circle concentric with said blade wheel central axis and in substantially uniformly spaced relationship to each other, said pivot axes being substantially parallel to each other and also parallel to said central axis, each of said blades being capable of an oscillating movement about its pivot axis, adjustable control means common to all of said blades and movable selectively from a central position coaxial with said central axis of said blade wheel body into any one of a plurality of positions eccentric with regard to said central axis of said blade wheel body and vice versa to govern the oscillating movement of said blades, each of said blades comprising a pivot and being oscillatable about a middle position of the blade in which the respective blade

is tangential to the circle along which the pivot axes of said blades are arranged, a plurality of blade actuating linkage systems respectively operatively connecting said adjustable control means with said blades so that each of said blades will be operable in response to a rotation of said wheel body and while said adjustable control means occupies any of its possible positions to carry out an oscillating movement having the predetermined magnitude of the blade angles which correspond to the respective circular positions of the pivot axes of the blades during their circular movement with said blade wheel body, each of said blade actuating linkage systems comprising at least one lever operatively connected to the respective blade pivot and also comprising a connecting rod linked to said lever, each of said blade actuating linkage systems furthermore comprising a two-arm lever having one of its arms connected to said connecting rod and having its other arm pivotally connected at the center of said adjustable control means, means including a link between the lever and wheel body pivotally connecting the two-arm lever in the region of the junction of the two arms thereof to a point on the blade wheel body, said point on the wheel body being located in a radial plane passing through the axis of rotation of said wheel body and through the axis of the pivotal connection of the respec-

tive blade with said blade wheel body and also being located between said axes, the arrangement being such that for each blade and the linkage system pertaining thereto, with regard to the direction of rotation of said wheel body, the lever and rod and at least that arm of the two-arm lever which is linked to said rod, all pertaining to said blade actuating linkage system in the central position of said control means, are located behind said radial plane.
